(57) **CLAIM**

The ornamental design for an angel wings sculpture, as shown and described.

DESCRIPTION

FIG. 1 is a 3/4 front perspective view of new ornamental design for an angel wings sculpture.

FIG. 2 is a front elevational view of FIG. 1.

FIG. 3 is a rear elevational view of FIG. 1.

FIG. 4 is a left side elevational view of FIG. 1.

FIG. 5 is a right side elevational view of FIG. 1.

FIG. 6 is a top plan view of FIG. 1; and,

FIG. 7 is a bottom plan view of FIG. 1.

The broken lines shown illustrate portions of the angel wings sculpture that form no part of the claimed design.
